GAME BOARD

Israel R. Paris, Washington, D. C.

Application October 31, 1938, Serial No. 238,004

11 Claims. (Cl. 35—8)

The present invention relates generally to a plate or board which is employed in association with a sheet having printed thereon card insignia, arranged to form the several hands of a game of bridge or any other card game; the plate having sight openings arranged to register with the printed insignia so as to display the insignia through the plate. In this type of device, the sight openings have devices associated therewith for indicating the progress of the play of the hand, such devices being preferably arranged in the form of sliders disposed within the sight openings, which by their position indicate whether the particular card displayed through any sight opening has been played or remains to be played. In the preferred form of this type of device, the sheet bearing the printed insignia of the playing cards also bears a number associated with each card, the numbers serving to indicate the order of play of the cards; each number thereby indicating the number of the trick upon which each card is played. In such devices the slider is made to operate so that in one position it covers the number but permits the display of the card arrangements. In the other position it covers the card and permits the display of the number associated with the card.

In addition, such plates or boards are also provided with means for displaying the process and progress of the bidding appropriate to each hand. The sheet or sheets associated with such a board have the bidding printed thereon in association with each hand. The board itself is therefore provided with means for displaying the bidding one step at a time, so as to indicate the progress of the bidding.

The plate also contains a device for indicating the tricks taken by the two opposing sides of the game and should also contain some other means to display other information which appears printed on the sheet associated therewith.

It is the object of the present invention to simplify the construction of this type of playing board so as to reduce the cost of manufacture of the same, and also to so construct the playing board or plate so as to facilitate and reduce the expense involved in the assembly of the large number of elements that enter into the construction.

Another object of the invention is to provide a plate or board of the type above described which is substantially rigid and still simple in construction, presenting an attractive appearance and which may be made to register with the printed sheet with great facility and substantial accuracy.

A further object of the invention is to provide a book whether in loose leaf form or otherwise in which each leaf or page has a bridge game or deal printed thereon and discussed, the book also having associated therewith a plate suitably slotted to display the card insignia therethrough, the plate also carrying movable devices to indicate whether any given card has been played or remains to be played and which generally aid in indicating the progress of the game.

In the drawings:

Fig. 1 is a plan view of my game board secured to the cover of a book.

Fig. 2 is an edge view of the same.

Fig. 3 is a plan view of the board secured to the pages of a book.

Fig. 4 is a plan view of the board secured in a loose leaf type of book.

Fig. 5 is a section on line 5—5 of Fig. 1.

Fig. 6 is a section on line 6—6 of Fig. 5.

Fig. 7 is a perspective view of one of the sliders.

Fig. 8 is a partial plan view of a slightly modified form of board and

Fig. 9 is a view showing the blank of the plate illustrated in Fig. 8.

The boards shown in both forms of the invention disclosed herein have for one of their essential features that they are constructed of a single sheet of suitable material such as metal or the like and that the slots or sight openings are so disposed in the sheet that the sliders may be inserted into these slots or sight openings with great facility and by an extremely simple manipulation. While these boards are preferably made of a sheet of metal of suitable gauge or thickness, they may obviously be made of any other suitable material.

In both forms of the invention shown herein, the marginal portions of the board are provided with one or two additional layers of metal. In one form of the invention, these additional layers are continuous with the original metal sheet of which the board is made and are merely folded or crimped over to yield the structure shown. In the other form of the invention, this reinforced material takes on the form of a folded over strip which is hammered onto the marginal portions of the slotted sheet. In both cases, these reinforcements serve in the first instance the function of properly closing the ends of the slots or sight openings after the sliders have been assembled in such slots, and these reinforcements also serve to lend rigidity to the board.

Referring now to the form shown in Fig. 1, the board comprises a flat and relatively thin metal

sheet or a sheet of any other suitable material such as cardboard or the like 10, which is provided with slots or sight openings 11, which it will be seen extend all the way out to the edge of the sheet 10, so that these slots or sight openings 11 may be spoken of as open-ended, and are separated from each other by the partitions 2. These rows of slots 11 are disposed as shown along the outer edges of the substantially oblong sheet 10, the number of slots in each row depending upon the nature of the game in which the board is to be employed.

In addition to the openings 11 which are designed to permit the display of printed card insignia are numbers associated with such insignia, the board or plate 10 also has other openings together with suitable devices for the display of other printed information that appears on the same sheet which bears the card insignia. Such printed information may comprise the bids made by each hand. For this purpose, a circular series of punched out openings 13 is disposed immediately adjacent each row of slots 11, these being covered by a centrally pivoted disc 14 which has one opening 15 for successive registry with the openings 13. It will be understood that the printed sheet which is to be employed in association with the present playing board will have the bids will be disposed in registry with the openings 13. The disc 14 may then be moved first into registry with the first one of the openings 13 so as to display the first bid and then it may be moved successively with the remaining openings so as to display the bids successively. In addition, the plate 10 also bears the centrally pivoted discs 16 which bear numbers on their marginal portions designed to cooperate with the pointers 17 for the purpose of keeping score of the progress of the game. The plate also has the openings 18 and 19 which are designed to display additional data but may be printed on the printed sheet associated therewith, such as an indication of the dealer and other information about the game.

The sliders 20 employed in the present invention are illustrated in Fig. 7 and comprise the main body portion 21 and the upstanding ears 22, one at each end thereof, each ear having the cut out portions 23 as shown. The width of the slider is greater than the width of the openings 11, so that when inserted in such openings the main body portion 21 overlaps on each side of the opening onto the partitions 12. The width, however, is such that the sliders are free of each other and do not engage each other when installed and separated. The main body portion 21 of the slider is preferably bowed upwardly as shown, with the result that they engage the partitions 12 with substantial friction and for that reason will maintain their positions.

It will now be understood that when the plate 10 has open-ended slots or sight openings 11 disposed in the marginal portions of the plate, it becomes a simple matter to insert the sliders 20 so that the body portions 21 of such sliders are disposed on one side of the plate while the ears 22 are all exposed on the upper side of the plate so as to permit the ready manipulation of such sliders.

After all of the sliders have been assembled with the plate, then the channel-shaped elements 25 are placed over the marginal portions of the plate 10 so as to close the ends of the sight open-

ings 11 and the elements 25 are then hammered down to firm and permanent engagement with the plate, or if desired other suitable means may be employed for this purpose, such as solder or the like, thereby finishing the total assembly. The channel-shaped elements 25 may overlap each other at the corners for the purpose of imparting to the board a greater degree of rigidity.

The underside of the channel-shaped portions 25 also serves as a spacer so that the board when it rests on the sheet has its main body portion spaced from the sheet so as to permit free movement of the sliders 20. For this purpose, it may also be desired that the sliders 20 be made of a gauge of metal which is somewhat thinner than the metal of which the board 10 is made, or the metal of which the channel portions 25 are made.

The form of the invention shown in Figs. 8 and 9 will be best understood by first referring to Fig. 9. Plate 30, substantially oblong in shape, is cut so that it is provided with a small cut out corner portion 31. The sight openings 32 are cut to approximately the shape shown, in that they are each provided with an enlargement 33 at the end adjacent the margin of the plate 30. The enlargement 33 is designed so that it may readily receive one of the ears 22 of the sliders 20. The dotted lines 34 indicate the marginal portions 35 and constitute the folding line for portions 35. In the preferred construction, the slots 32 together with the enlargements 33 should preferably be spaced from the fold line 34. With the plate 30 in this form, the sliders 20 may be readily inserted by manipulating the same on the back of the plate by first inserting the ear 22 and pushing the slide along so that the openings 23 ride on the partitions 36, this being followed immediately by pressing the other ear 22 similarly into the enlargement 33 and pushing the slide forward so that all the openings 23 ride on the partitions 36. After all of the slides 20 have been assembled in the way described with the board, then the marginal portions 35 are folded over onto the front face of the plate as is shown in Fig. 8. This portion 35 serves to reinforce the plate, to render the same substantially rigid, and to close off the enlargements of the slots. The portions 35 should preferably be pressed down in such a manner that its upper face is approximately in the plane with the upper face of the main body portion of the plate 30 thereby displacing the marginal portion on the lower face somewhat below the level of the lower face of the plate 30, for the purpose of giving the sliders some freedom of movement between the plate 30 and the printed sheets with which the plates are to be used.

As has already been set forth in my copending Patent 2,135,411 the game board may be employed in combination with a book having the desired data printed on the pages of the book. Thus Figures 1, 2 and 3 show a game board, which although illustrated herein as of a construction more specifically disclosed herein, may of course be of a construction disclosed in the said patent, associated with the conventionally bound book and Fig. 4 shows such a board associated with a loose leaf book.

For use in a loose leaf book the game board 10 may have two or more openings 42 along one edge or along two parallel edges, these openings serving to engage the customary loose leaf ring 44.

Instead of a loose leaf book, a customary bound book may be employed. The board when so em-

ployed may be provided with a spring 46 at the top and bottom edge which will serve to grip the upper and lower edges of the cover 48 of the book 50. The same spring will serve to grip 5 lightly the assembled sheets in the book when the board is employed against a page of the book, to properly locate the board and prevent it from sliding on the page. If desired, the board may be provided with a flexible hinge 52 which attaches one edge of the board to the lower cover 10 and the board is thereby permanently associated with the book.

Having thus described my invention, I claim:

1. A device of the class described comprising 15 a substantially rectangular plate having open-ended elongated openings in its marginal portions, a partitioning strip between adjacent openings, a slide disposed in each of such openings and carried by the adjacent partitioning strips, 20 and a substantially rigid flattened channel shaped metallic member disposed along each edge of said board enclosing and gripping the ends of the partitions and serving to close the ends of the openings and to impart rigidity to 25 the board.

2. A device of the class described comprising a board having a substantially rectangular main body portion, said body portion having a plurality of elongated openings disposed in its marginal portions, said openings having enlargements 30 at their outer ends, slides carried by the board slidable within such openings, and a folded over marginal portion which serves to close the enlargements in the openings, said enlargements 35 serving to facilitate the insertion of the slides into the openings before folding the marginal portion.

3. A game board having a plurality of through sight openings for cooperation with a sheet bearing 40 printed data in registry with said openings, said board comprising a substantially rectangular main body portion made of relatively flexible material and having elongated openings disposed in its marginal portions, the longer dimension of 45 such openings being disposed perpendicularly to the adjacent edge, partitioning strips disposed between adjacent openings, sliders disposed in said openings and carried by the adjacent partitioning strips, and substantially rigid, flattened, 50 longitudinally folded, metal parts carried by said board on the edges thereof serving to close the ends of the elongated openings and to render the board substantially rigid.

4. In combination a book, a plate constituting 55 a cover for the book, said plate having dimensions approximating the dimensions of the leaves of the book and being removable from the cover position and insertible into the book in association with a leaf thereof, means for retaining the 60 plate in position within the book and fixedly with relation to a selected leaf thereof, said plate having a multiplicity of sight openings permitting the display of printed data on the leaf of the book, said plate also having sliders operable 65 to cover or display some of said printed data.

5. In combination a loose leaf book, means holding said loose leaves together, a rigid cover plate for said book having dimensions approximating the dimensions of the leaves of the book 70 and having openings engaged by said means for holding said cover plate in position, said cover plate having a multiplicity of sight openings for display of printed data on the leaves of the book, said plate also having slides selectively to display 75 or cover some of said printed data, whereby said

plate may be removed from the cover position and inserted in any other portion of the book for association of said plate with the printed data on any page thereof.

6. In combination, a book, a plate having dimensions approximating the dimensions of the leaves of the book and insertible into the book in association with any leaf thereof, said plate having a plurality of sight openings for the display of printed insignia on the leaf of the book, 10 sliders operable in said sight openings to cover or display said insignia as desired, flexible means connecting one edge of the plate to an edge of a cover, and a resilient clip carried by at least one other edge of the plate for engagement with the 15 book to retain said plate in position in said book to maintain registry between said sight openings and the insignia.

7. A book for self instruction in the game of bridge, said book comprising, as an integral element thereof, a plate having dimensions approximating the dimensions of the leaves of the book and having four groups of openings disposed along the sides of a square, the leaves of said book each bearing a set of playing card insignia 20 arranged similarly to said openings along the four sides of a square to form the four hands of a bridge game, said plate and book having detachably cooperating means for adjustably and fixedly positioning the plate within the book to 25 overlie any desired leaf to display the bridge game thereon through said openings, and slides carried by said plate in each opening movable to cover or display the insignia and to indicate whether the card has been played. 30

8. A book for self instruction in the game of bridge, the book having a pair of covers and leaves bearing playing card insignia arranged to form the four hands of a bridge game; in combination with a plate of substantially the same 40 size as the leaves and having a plurality of sight openings for the display of said insignia there-through, said plate and book having cooperating means for removably fixedly positioning the plate within the book in a position to overlie any desired leaf and to hold the same in a position to obtain registry between its sight openings and said insignia, and two-position indicators carried by said plate adjacent each opening to indicate the 45 progress of the game. 50

9. A loose leaf book for self instruction in the game of bridge, the book having leaves bearing playing card insignia arranged along the four sides of a square to form the four hands of a bridge game and rings holding said leaves in 55 suitable assembly; in combination with a plate having four groups of sight openings similarly disposed along the sides of a square for registry with said insignia, and a slide in each opening movable to cover or display the insignia to indicate whether the card has been played, the plate having marginal openings for engagement with the rings for adjustably, removably positioning the plate within the book to overlie any desired leaf to display the bridge game thereon 60 65 through said openings.

10. A loose leaf book for self instruction in the game of bridge, the book having leaves bearing playing card insignia arranged along the four sides of a square to form the four hands of a 70 bridge game and rings holding said leaves in suitable assembly; in combination with a plate having four groups of sight openings similarly disposed along the sides of a square for registry with said insignia, and a slide in each opening 75

- movable to cover or display the insignia to indicate whether the card has been played, the plate having marginal openings in each of two parallel edges, the openings being spaced in registry with the binding rings, and serving for selective engagement with the rings for adjustably, removably positioning the plate within the book to overlie either side of any desired leaf to display the bridge game thereon through said openings.
11. In combination, a loose leaf book, a rigid cover plate for said book having dimensions approximating the dimensions of the leaves of the book, means holding said loose leaves and said

cover plate in book assembly, said loose leaves bearing playing card insignia arranged along the four sides of a square to form the four hands of a bridge game, said cover plate having four groups of sight openings similarly disposed along the sides of a square for registry with said insignia, a slide in each opening movable to cover or display the insignia to indicate by its position whether the card has been played, whereby said plate and any desired leaf may be associated to display the bridge game thereon through said openings. 5 10

ISRAEL R. PARIS.
